UNITED STATES PATENT OFFICE.

CHARLES ERNEST JONES, OF CHICAGO, ILLINOIS.

DESIGN FOR AN EXTENSION-BRACKET FOR LIGHTING-FIXTURES.

50,692.

Specification for Design.

Patented May 1, 1917.

Application filed March 6, 1917. Serial No. 152,940. Term of patent 3½ years.

To all whom it may concern:

Be it known that I, CHARLES ERNEST JONES, a citizen of the United States, residing at Chicago, in the county of Cook and State of Illinois, have invented a new, original, and ornamental Design for an Extension - Bracket for Lighting - Fixtures, of which the following is a specification, reference being had to the accompanying drawing, wherein—

The figure is a front elevation, of an extension bracket for lighting-fixtures, showing my new design.

I claim as my invention:

The ornamental design for an extension bracket for lighting fixtures, as shown.

CHARLES ERNEST JONES.
